UNITED STATES PATENT OFFICE

ISIDORE E. TONIEWICZ AND MICHAEL LIZON, OF BUFFALO, NEW YORK

TOOL HOLDER GUARD

Application filed March 19, 1931. Serial No. 523,874.

This invention relates to a tool holder guard, and more particularly to a device of this character adapted to be applied to the holder of a lathe or similar machine. When a workman is operating a lathe or similar machine, the cuttings are liable to fly upwardly and rearwardly, especially if very hard metal is being cut and since these cuttings are often very hot, they are liable to injure the workman either by cutting or burning him. This is particularly true if a cutting should lodge in a workman's eye. Some workmen wear goggles in order to protect their eyes, but this has been found unsatisfactory as the goggles sometimes interfere with a workman's sight and prevent him from clearly seeing the work being done.

Therefore one object of the invention is to provide a guard which may be easily applied to a tool holder and will serve very effectively to prevent cuttings from striking a workman operating a lathe or other machine.

Another object of the invention is to so form the guard that a portion thereof extending upwardly over a cutter or other tool may be formed of transparent material, thereby allowing the workman to see the tool during a cutting operation and at the same time be protected from particles of metal thrown upwardly and rearwardly during a cutting operation.

Another object of the invention is to provide a device of this character which is very simple in construction and may be formed of sheet metal and thereby cheaply produced.

The invention is illustrated in the accompanying drawing, wherein:

Figure 1 is a side elevation showing the improved shield applied to a tool holder.

Figure 2 is a top plan view of the shield.

Figure 3 is a front elevation of the shield.

Figure 4 is a perspective view of the improved shield with a frame carrying a sheet of transparent material and forming part of the shield detached.

Figure 5 is an enlarged sectional view taken along the line 5-5 of Figure 2.

Figure 6 is a view of the blank from which the body portion of the shield is formed, and

Figure 7 is a view of the blank from which the frame carrying the transparent sheet is formed.

The improved shield has been shown applied to a tool holder 1 which is of a conventional construction and is formed at its forward end with a socket in which a cutter 2 is fitted and secured by a set screw 3. The shield is applied to the holder as shown in this view and has an attaching portion 4 which extends transversely across the top of the holder and is provided with arms 5 extending rearwardly.

The arms are spaced from each other a distance corresponding substantially to the diameter of the set screw 3 and fit between the head of the set screw and the upper face of the holder. Therefore when the set screw is tightened to secure the cutter to the arms they will be firmly gripped by the head of the screw and the shield securely held in place.

The body portion of the shield is formed from a sheet metal blank shown in Figure 6 and this blank is cut along lines 6 to provide portions which when bent downwardly along the dotted line 7 form side wings or guards 8 disposed at opposite sides of the tool holder. Outer side portions 9 of the side wings or guards are bent along the dotted lines 10 to form deflectors which extend forwardly at an incline in diverging relation to each other and serve very effectively to cause particles of metal which strike the side wings to be deflected forwardly and prevented from striking a workman. The intermediate portion of the blank is cut out from its forward end, thereby forming arms 11 connected at their inner ends by a bridge 12 and when this intermediate portion of the blank is bent upwardly along the dotted line 7, the arms 11 will project forwardly at an upward incline. Since the inner ends of the arms are connected by the bridge 12 there will be no danger of these arms breaking off.

In order to permit a workman to see the cutter or other tool 2 there has been provided a sheet 13 formed of celluloid or any other suitable material. This transparent sheet is fitted into a frame formed from the blank

shown in Figure 7. This blank has side portions 14 connected by a narrow strip 15 and when the side portions are folded along the dotted lines 16 a frame will be formed having side bars 17 connected by an inner end bar 18. The side bars are formed with guides or jaws 19 between which side edge portions of the transparent sheet are engaged and by referring to Figure 5 it will be seen that the 10 arms 11 are also engaged by these jaws.

The inner end bar 18 overlaps the bridge 12 and therefore the frame will be firmly engaged with the arms 11 and may be held in place either by frictional binding or solder 15 may be applied to firmly hold the frame in engagement with the arms and bridge.

The strip of transparent material may be tinted in order to prevent a workman's eyes 20 being injured by looking at the hot metal cut by the tool 2. This sheet of transparent material may fit in the frame with sufficient looseness to permit it to be removed and a new one applied when necessary.

Outer side portions 20 of the side bars 17 25 are bent to extend forwardly in diverging relation to each other thereby providing flanges or wings which will serve very effectively to prevent metal particles flying rearwardly from sides of the shield after striking the transparent sheet.

We have therefore provided a shield so constructed that there will be no danger of a workman being injured by metal particles thrown off by a cutter or other tool when 30 working at a lathe and at the same time have provided a shield which is very simple in construction and easy to apply.

We have further provided a shield so constructed that a workman will not be prevented from seeing the end of the tool.

What is claimed is:

1. A guard for a tool holder comprising an attaching portion adapted to be firmly secured upon a tool holder, wings at opposite sides of said attaching portion disposed transversely thereof and extending downwardly therefrom, a portion projecting upwardly at a forward incline from the front of said attaching portion between said wings, and having arms spaced transversely from each other and a bridge connecting inner ends of the arms and joined to the attaching portion, a frame having side bars fitting upon said arms in straddling relation thereto and an inner end bar overlapping said bridge and a transparent sheet in said frame having its inner end overlapped by the inner end bar and its side portions engaged between said arms and 60 portions of the side bars.

2. A guard for a tool holder comprising an attaching portion adapted to be firmly secured upon a tool holder, wings at opposite sides of said attaching portion disposed 65 transversely thereof and extending down-

wardly therefrom, a portion projecting upwardly at a forward incline from the front of said attaching portion between said wings, and having arms spaced transversely from each other and a bridge connecting inner ends of the arms and joined to the attaching portion, a frame having side bars fitting upon said arms in straddling relation thereto and an inner end bar overlapping said bridge and a transparent sheet in said frame having its inner end overlapped by the inner end bar and its side portions engaged between said arms and portions of the side bars, said wings having outer side portions projecting from said attaching portion and bent to extend forwardly at an incline in diverging relation to each other, and outer side portions of the side bars of said frame being bent to extend forwardly at an incline in diverging relation to each other. 75 80 85

3. A guard for a tool holder comprising an attaching portion adapted to be firmly secured upon a tool holder, wings at opposite sides of said attaching portion disposed transversely thereof and extending downwardly therefrom, a portion projecting upwardly at a forward incline from the front of said attaching portion between said wings, and having arms spaced transversely from each other and a bridge connecting inner ends of the arms and joined to the attaching portion, a frame having side bars fitting upon said arms in straddling relation thereto and an inner end bar overlapping said bridge and a transparent sheet in said frame having its inner end overlapped by the inner end bar and its side portions engaged between said arms and portions of the side bars, the side bars of said frame having portions projecting from outer side edges of said arms and bent to extend forward at an incline in diverging relation to each other. 95 100 105

4. A guard for a tool holder comprising an attaching portion adapted to be firmly secured upon a tool holder, depending wings at opposite sides of said attaching portion adapted to straddle said tool holder, outer side portions of the wings extending laterally beyond said attaching portion and bent to project forwardly at an incline in diverging relation to each other, arms projecting upwardly at a forward incline from said attaching portion, a frame carried by said arms, and a transparent sheet carried by said frame. 110 115 120

5. A guard for a tool holder comprising an attaching portion adapted to be firmly secured upon a tool holder, depending laterally extending wings at opposite sides of said attaching portion adapted to straddle said tool holder and forming side guards, a portion projecting upwardly at a forward incline from the front of said attaching portion between said wings, a frame carried by the last- 125 130

mentioned portion, and a transparent sheet carried by the frame.

6. A guard for a tool holder comprising an attaching portion adapted to be firmly secured upon a tool holder, depending laterally extending wings at opposite sides of said attaching portion adapted to straddle said tool holder and forming side guards, a shield projecting upwardly at a forward incline from the front of said attaching portion, and a transparent sheet carried by the shield.

7. A guard for a tool holder comprising an attaching portion adapted to be firmly secured upon a tool holder, depending laterally extending wings at opposite sides of said attaching portion adapted to straddle the tool holder and forming side guards, said wings being provided with terminal angularly disposed deflectors, a shield projecting upwardly at a forward incline from the front of said attaching portion between said wings and having arms spaced transversely from each other and a bridge connecting inner ends of the arms and joined to the attaching portion, a frame engaged upon said arms with its inner end overlapping said bridge, and a sheet of material carried by said frame.

In testimony whereof we affix our signatures.
